UNITED STATES PATENT OFFICE

HARRY AGLOW, OF PHILADELPHIA, PENNSYLVANIA, ASSIGNOR TO GILL GLASS & FIXTURE COMPANY, A CORPORATION OF DELAWARE

DESIGN FOR AN ILLUMINATING GLOBE

Application filed October 31, 1930. Serial No. 37,467. Term of patent 14 years.

To all whom it may concern:

Be it known that I, HARRY Aglow, a subject of the King of Great Britain, and a resident of Philadelphia, in the county of Philadelphia and Commonwealth of Pennsylvania, have invented a new, original, and ornamental Design for Illuminating Globes, of which the following is a specification, reference being had to the accompanying drawing, forming a part hereof.

In the drawings:

Figure 1 is a side elevational view of the illuminating globe; and

Figure 2 is an elevational view of the same taken from either the front or the rear.

I claim:

The ornamental design for an illuminating globe substantially as shown.

HARRY AGLOW.
